UNITED STATES PATENT OFFICE.

HENRY E. WAEHLTE, OF SAN JOSÉ, CALIFORNIA.

STIRRUP.

SPECIFICATION forming part of Letters Patent No. 233,647, dated October 26, 1880.

Application filed June 19, 1880. (No model.)

To all whom it may concern:

Be it known that I, HENRY EMIL WAEHLTE, of San José, in the county Santa Clara and State of California, have invented certain new and useful Improvements in Safety-Stirrups; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved safety-stirrup. Fig. 2 is a detail view of the foot-plate detached from the bail, and Fig. 3 is a detail view of the bail.

Corresponding parts in the several figures are denoted by like letters of reference.

This invention relates to safety-stirrups; and it consists in certain improvements in the construction of the same, which will be hereinafter fully described, and particularly pointed out in the claim.

In the drawings hereto annexed, A represents the bail, which is provided at its upper end with a slot, B, for the reception of the stirrup-strap. One of the arms C of the bail is jointed near its lower end, the hinged piece D being capable of swinging in an outward direction, as shown. The hinged piece D is provided at its lower end with an opening or eye, F, to receive a hook, G, formed upon one

end of the foot-plate H. At its other end the latter is provided with a stud or stem, I, having beveled flanges or threads J, and fitting in 35 a correspondingly-constructed recess or opening, K, in the lower end of the unjointed arm of the bail.

The operation of my invention will be readily understood. In the event of the horseman 40 being thrown the swinging around will detach one end of the foot-plate from the stirrup-bail, and the other end, being attached to the hinged piece D, will cause the foot-plate to swing free and thus release the foot. After 45 afterward the stirrup may be readily restored to its original condition.

Having thus described my invention, I claim and desire to secure by Letters Patent of the United States—

The combination, with the bail A, having threaded recess or opening K, and hinged piece D, provided with eye F, of the foot-plate H, having hook G and threaded stud or stem I, substantially as and for the purpose herein 55 shown and specified.

In testimony that I claim the foregoing as my own I have hereto affixed my signature in presence of two witnesses.

HENRY EMIL WAEHLTE.
